(57) **CLAIM**

The ornamental design for a dispenser for liquid soaps, shampoos, conditioners, and other lotions and liquids, as shown and described.

DESCRIPTION

FIG. 1 is a front perspective view of a dispenser showing my new design.

FIG. 2 is a front elevational view as viewed from the left in FIG. 1.

FIG. 3 is a rear elevational view as viewed from the direction opposite that of FIG. 2.

FIG. 4 is a side elevational view taken from the left in FIG. 3, the opposite side being a mirror image thereof.

FIG. 5 is a top plan view as viewed from the top in FIG. 4; and,

FIG. 6 is a bottom plan view as viewed from the bottom in FIG. 4.
